UNITARY ILLUMINATING DEVICE

Chester H. Braselton, New York, N. Y., assignor
to Sirian Lamp Company, Newark, N. J., a cor-
poration of Delaware

Application August 25, 1932, Serial No. 630,382

7 Claims.

(Cl. 176—1)

This invention relates to illuminating devices and particularly to such devices in which two or more colors are blended together to produce a third, and is a continuation in part of my co-pending application Serial No. 611,817, filed May 17th, 1932.

One of the objects of the invention is to provide a unitary lamp structure in which several electrical discharges may be carried on independently of each other.

Another object of the invention is to provide an electric illuminating device in which two or more colored lights may be produced independently of each other in one unitary lamp structure.

Still another object of the invention is to provide an electric lamp having a plurality of envelopes all mounted upon one base so that the lamp as a unit may be screwed into a standard lamp receiving socket.

Other objects of the invention and objects relating to the construction and assembly of the various parts will be apparent as the description of the invention proceeds.

One embodiment of the invention has been illustrated in the accompanying drawing in which:

Fig. 1 is a sectional side elevation of my improved lamp;

Fig. 2 is a plan view of the lamp with the cap removed;

Fig. 3 is a sectional plan view taken on the line 3—3 of Fig. 1; and

Fig. 4 is an expanded view of the three envelopes in perspective showing the manner of making the electrical connections between them.

Broadly the invention comprises the provision of two or more envelopes each having a pair of electrodes and containing an ionizable gas so chosen as to produce a particular color of light when an electric current is discharged through it, with means to provide a continuous metallic path for the current, in addition to the path through the gas, to maintain the potential between the electrodes in the discharge envelopes and to insure the lamp starting at any time.

In the embodiment of the invention shown I provide three separate and independent envelopes 10, 11, and 12, each formed with a cross section corresponding to a sector of a third of a circle, as clearly indicated in Fig. 3, so that when the three envelopes are placed together they form a complete cylinder. Each of the envelopes is provided with an angular press 13 at each end thereof whose sides may conform to the straight sides of the envelope so as to fit together back to back

as indicated in Figs. 2 and 3. When the three envelopes are placed together, so as to form a single complete cylinder, the lower ends may be secured in a threaded base plug 14 by means of suitable cement 15, while the upper ends may be secured in a cap member 16 also with suitable cement 17, the electrical connections being made within the cap 16 and the base plug 14.

The envelope 10 may have an electrode 18 formed of a circular disc of metal, such as nickel, iron, tungsten, or the like, mounted at the lower end thereof upon a support rod 19 which is sealed through the lower press. At the other end of the envelope a filamentary resistance wire or heater element 20 may be mounted between two support rods 21 and 22 which are likewise sealed through the upper press. The envelope 10 may be filled with an ionizable gas having a sufficient pressure to cause a discharge to appear between the electrode 18 and the resistance wire 20 when a suitable potential is produced between the two. Any ionizable gas may be used within the bulb but I may prefer to use one or more of the monatomic gases such as neon, helium, argon, krypton, or xenon, or a metal vapor such as one of the vapors of sodium, caesium, mercury, rubidium, or mixtures of such vapors. As an example of one particular type of lamp the envelope 10 may be filled with neon gas at a pressure somewhat under 5 mm. of mercury.

The envelope 12 may be exactly similar in construction to the envelope 10 but may contain a different gas. Thus an electrode 23 similar to the electrode 18 in the envelope 10 may be mounted on a support rod 24 which is sealed through the lower press of the envelope 12 while a filamentary resistance wire or heater element 25 may be mounted between two support rods 26 and 27 which are sealed through the upper press of the envelope 12. The envelope 12 may, in the present case, be filled with mercury vapor at a pressure which will equal about three times the pressure of the neon gas at operating temperatures. The mercury may be inserted in the envelope 12 in a well known manner, as by leaving a drop of mercury in the envelope when the envelope is sealed off.

The third envelope 11 may be formed similarly to the others but a pair of support rods 28 and 29 may be sealed through the lower press while a second pair of support rods 30 and 31 may be sealed through the upper press. A filamentary resistance wire 32 may be supported longitudinally of the envelope between the support rods 28 and 30 while a second filamentary resistance wire 33

33 may be similarly supported between the two support rods 28 and 31. The envelope 11 may preferably be exhausted or provided with a relatively non-conductive inert gas, such as nitrogen, so that the filaments 32 and 33 may be heated even to a high light emitting temperature without causing any discharge inside of the envelope.

With the envelopes constructed as explained above the three may be positioned in contact with each other as indicated in Figs. 2 and 3 and while held in this position the electrical connections may be made. Thus the upper ends of the support rods 22 and 27 in the envelopes 10 and 12 respectively may be welded together by bending them so as to cross each other and welding at the point of crossing. Likewise the upper end of the support rod 21 of the envelope 10 may be welded to the upper end of the support rod 30 of the envelope 11 and the upper end of the support rod 31 of the envelope 11 may be welded to the upper end of the support rod 26 of the envelope 12. At the lower ends of the envelopes, leading in wires 34 and 35 may be connected to the support rods 28 and 29 respectively of the envelope 11 and wires 36 and 37 may be connected respectively to the support rods 19 and 24 of the envelopes 10 and 11. The wire 36 may also be connected to the wire 34 and the wire 37 to the wire 35. The connections may be made in the base of the lamp by soldering the wire 34 to the side of the base and the wire 35 to the center contact 38 thereof.

Thus connected current may enter the wire 34, pass up through the support rod 28 in the envelope 10, through the filamentary resistance wire 32, through the support rod 30 at the top of the envelope, into the support rod 21 on the top of the envelope 10, down through the resistance wire 20 in that envelope, up through the support rod 22 and into the support rod 27 of the envelope 12, down through the resistance element 25 in that envelope, up through the support rod 26 and into the support rod 31 of the envelope 11, down through the filamentary resistance wire 33, through the support rod 29 in the bottom of the envelope 11, and out through the lead-in wire 35. This will energize the two filamentary resistance wires 32 and 33 and also the heater elements 20 and 25, raising all of them to a high temperature.

Inasmuch as the electrode 18 of the envelope 10 is connected to the wire 34 and therefore to one side of the filament 32 while the other side of that filament is connected to the resistance element 20 in the envelope 10, there will be a drop of potential between the element 20 and the electrode 18 in that envelope depending on the resistance of the filament 32. This drop of potential aided by the heat produced by the element 20 will cause a discharge to occur between that element and the electrode 18 through the neon gas which will have a reddish tint.

A similar phenomenon occurs in the envelope 12 where the electrode 23 is connected to one side of the filament 33 and the heater element 25 is connected to the other side of it, thus making a difference in potential between the heater element 25 and the electrode 23 corresponding to the resistance of the filament 33. A discharge will then occur between the heater 25 and the electrode 23 through the mercury vapor which will have a bluish-green tint.

The combined light of the envelopes 10 and 12 may be such as to produce a white light if the proportion of the gases are as indicated above

with about three times as much mercury vapor as neon when the lamp is operating.

While the filaments 32 and 33 have been indicated as being identical, the resistance of each should be predetermined so as to get the proper potential drop through the gas in the cooperating envelope. In some instances, therefore, one wire might be shorter than the other or they may be made of different resistance materials. They also may be arranged to emit light if desired or they may be so designed that they are not raised to light emitting temperature but merely act as a ballast for the other two envelopes.

Also if desired the color of the light emitted by the filaments 32 and 33 may be filtered by suitably coloring the glass of that envelope so that light from the envelope will be colored with one of the three primary colors, for instance, the other two envelopes being arranged to emit the other two primary colors so that the three envelopes together may give a white light. With the arrangement described above, however, the two envelopes 10 and 12 combine to produce the white light by the neon discharge in one and the mercury vapor discharge in the other and the light from the envelope 11 is used solely to augment the total amount of light.

The combination of colors may be varied considerably to produce not only white light but any desired colored effect by blending several colors together, or the lamp may be designed to produce a single color as may seem desirable.

While three envelope are shown and described the invention is not intended to be limited to the three envelopes but may include any number of discharge envelopes so connected and provided with ballasting resistances so that the discharges may be easily started and as easily controlled. Also while the two ballast resistances are shown as mounted in a single envelope they may each have an individual envelope, if desired, or the envelope or envelopes may be completely dispensed with and the ballast resistance may be arranged either in the base of the lamp or in the cap thereof.

The heating element used in the discharge bulb may be ordinary filaments of tungsten or other refractory metal, or they may be coated with electron emitting materials to increase the ionization in the neighborhood thereof so as to start the discharge at lower temperatures.

Many other modifications of the invention may be resorted to without departing from the spirit thereof, and I do not desire to limit myself to what has been shown and described except as such limitations occur in the appended claims.

What I desire to claim and secure by Letters Patent is:

1. In an electric lamp a pair of independent envelopes, a heater filament in each of said envelopes, means to connect said heater filaments together, a pair of resistance elements, means to connect one of said resistance elements to the end of one of said heater elements, means to connect the other of said resistance elements to the other of said heater elements, an electrode in each of said envelopes and spaced from said heater element, means to connect one of said electrodes to the opposite end of one of said resistance elements, and means to connect the other of said electrodes to the opposite end of the other of said resistance elements.

2. In an electric lamp an envelope, a heating element within said envelope, an electrode within said envelope spaced from said heating element,

a quantity of neon gas within said envelope, a second envelope positioned adjacent said first envelope, a heater element within said second envelope, an electrode within said second envelope and spaced from said heater element, a quantity of mercury within said second envelope, means to connect one end of each of said heater elements together, a resistance element, means to electrically connect said resistance element between the other end of one of said heater elements and the electrode corresponding to said heater element, a second resistance element, and means to electrically connect said second resistance element between the other end of said second heater element and its corresponding electrode.

3. In an electric lamp a plurality of envelopes arranged about a common axis, a pair of resistance elements mounted in one of said envelopes, a heater element mounted in another of said envelopes, means to connect one end of one of said resistance elements to one end of said heater element, an electrode mounted in said second mentioned envelope and spaced from said heater element, means to connect the other end of said first mentioned resistance element with said electrode, an ionizable gas in said second envelope, a second heater element in a third of said envelopes, means to connect one end of said second heater element with the free end of said first mentioned heater element, means to connect the other end of said second heater element with one end of the second of said resistance elements, a second electrode in said third mentioned envelope spaced from said second heater element, means to connect the opposite end of said second resistance element to said second electrode, and an ionizable gas in said third mentioned envelope.

4. In an electric lamp an envelope, a heater element within said envelope, an electrode within said envelope and spaced from said heater element, a quantity of neon gas at a pressure less than 5 mm. of mercury within said envelope, a second envelope mounted adjacent said first envelope, a pair of resistance elements within said

second envelope, means to connect one end of one of said resistance elements with one end of said heater element, means to connect the other end of said resistance element with said electrode, a third envelope mounted adjacent said first two envelopes, a heater element within said envelope, means to connect one end of said last mentioned heater element with the free end of said first mentioned heater element, means to connect the other end of said last mentioned heater element with one end of said second resistance element, an electrode within said third envelope and spaced from said heater element, means to connect the opposite end of said second resistance element to said last mentioned electrode, a quantity of mercury within said third envelope having a pressure less than 15 mm. of mercury at operating temperatures, and means to support said three envelopes on a common base.

5. A lamp structure comprising three elongated tube sections adapted to be positioned side by side, each tube having a sector cross section and reduced ends, the three sections when combined forming a cylinder, and a holding cap fastened over each of the three adjacent reduced ends of the sections whereby each section is restrained from axial or lateral movement with reference to the other.

6. A lamp comprising three independent and sealed tube sections, each section having a sector cross section and restricted ends, means at each end of said sections for holding them in inter-engaging relationship to form a tubular assembly, and a different conductive gas in each tube section.

7. A lamp comprising three independent and sealed tube sections fastened together at their ends, two of said tube sections containing a conducting gas and separated electrodes and the third section containing a solid conductor, and conducting means for connecting said electrodes and solid conductor together.

CHESTER H. BRASELTON.
